UNITED STATES PATENT OFFICE.

PAUL SCHWERIN, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed October 29, 1923. Serial No. 671,348.

This invention relates to electron discharge devices and pertains more especially to vacuum tubes having three electrodes.

The object of the invention is to simplify 5 the assembly of the electrodes in the manufacture of the device.

This object is attained by making the grid and anode substantially trough shaped. This permits mounting the filament upon its 10 support and subsequently disposing the other electrodes around the filament in operative relation thereto instead of first mounting the grid and anode and then threading the filament through them and attaching it to 15 its supports. The grid and anode are preferably mounted in the tube so that the open portions thereof face the press of the tube. The sides of the grid project sufficiently beyond the filament that it remains always in 20 the field between the cathode and anode despite sagging of the filament.

Referring now to the drawings, Fig. 1 discloses a vacuum tube constructed in accordance with the invention. Fig. 2 is a detail 25 of the grid electrode before completion, and Figs. 3 and 4 are detail views of modified forms of the grid.

A glass bulb 10 forms the enclosing vessel for the device and is compressed as at 11 to 30 form a stem for the leading-in and supporting wires. The free ends of the leading-in wires 12 and 13 are relatively widely separated and support the opposite ends of a filamentary cathode 14. The ends of the 35 leading-in wire 15 and the supporting wire 16 are attached to the opposite ends of a trough shaped grid electrode 17 which is disposed about the filament 14 so that it substantially surrounds the same. The ends of the 40 leading-in wire 18 and the supporting wire 19 are welded to projections 20 and 21 extending from the opposite ends of a trough shaped anode 22 which comprises a sheet metal stamping bent to the desired shape. 45 The grid and anode are supported substantially coaxially with the cathode having their open portions facing the stem or press 11.

The grid electrode 17 comprises, in effect, a series of U-shaped metallic members supported by longitudinal members. It may be composed, as shown in Figs. 1 and 2, of 50 a wire frame 23 having one end 24 projecting beyond the side of the frame, and a corresponding projecting member 25 welded to 55 the opposite end of the frame. A series of

U-shaped cross wires 26 extend between the side members and are welded thereto. The grid is preferably made up in the form of a plane member and is then bent around a mandrel into a substantial trough shape. 60 The projecting ends 24 and 25 are welded to the ends of the leading-in and supporting wires 15 and 16 to support the grid in operative relation to the filament.

The trough shape of the grid and anode 65 simplifies materially the assembly of the electrodes since the filament 14 may first be strung between its supports and the grid 17 and anode 22 may be slipped over the filament and fastened in proper position. This 70 75 obviates the delicate and tedious step of passing the filament through the grid and anode and attaching it to its supports. The grid and anode are of sufficient depth that the filament cannot sag below their edges when it expands upon being heated, or sags for any reason thereby maintaining the grid and anode substantially symmetrical with respect to the filament. This arrangement maintains an efficient relation of the electrodes at all times and insures that the field 80 between the anode and cathode is efficiently controlled by the grid voltage.

Figs. 3 and 4 disclose modified forms of grid. In Fig. 3, a single length of wire 27 is bent to form a succession of U-shaped 85 members connected by portions 29 and 30 of the wire so that a substantially trough shaped grid is provided. The ends of the wire 27 are extended beyond the edge of the 90 grid proper to provide supporting connections to the leading-in wires. In Fig. 4, the grid 31 comprises a stamping from a flat sheet of metal. The finished grid comprises a pair of side members 32 connected by the 95 plurality of U-shaped ribbons 33 which combine to form a substantially trough shaped grid. At opposite ends of the grid are provided projecting members 34 and 35 which may be welded to the supporting wires. 100 Manufacture of a grid, such as disclosed in Fig. 4, necessitates merely a blanking and bending operation and very materially reduces the labor involved in the manufacture of a grid since the need of any welding operations is entirely avoided.

What is claimed is:

1. In an electron discharge device, a press, pairs of lead-in wires sealed in said press, a straight filamentary cathode supported be- 110

tween one pair of lead-in wires and lying at right angles to the axis of the press, a trough shaped grid electrode located parallel to and effectively surrounding said filament 5 with its open side facing said press, said grid being supported at its opposite ends by a pair of said lead-in wires, and a trough shaped anode located parallel to and above said grid and filament and being supported 10 at its opposite ends by a pair of said lead-in wires.

2. In an electron discharge device, a press, pairs of lead-in wires sealed in said press, a straight filamentary cathode supported between one pair of lead-in wires and lying at right angles to the axis of the press, a grid 15 electrode comprising a metal plate having

portions cut out to provide a pair of longitudinal members and a plurality of lateral members connected to said longitudinal members, said lateral members being bowed intermediate their ends, said grid being located parallel to and over said filament and effectively surrounding the same and being supported at its opposite ends by a pair of said lead-in wires, and an anode comprising a sheet metal trough located parallel to and over said grid, said anode being supported at its opposite ends by a pair of said lead-in wires. 20 25 30

In witness whereof, I hereunto subscribe my name this 22nd day of October A. D., 1928.

PAUL SCHWERIN.
